UNITED STATES PATENT OFFICE.

THOMAS BINNIE DRYBROUGH, OF KENSINGTON, LONDON, ENGLAND.

COIN-FREED APPARATUS.

1,400,037.

Specification of Letters Patent. Patented Dec. 13, 1921.

Application filed April 23, 1920. Serial No. 375,949.

To all whom it may concern:

Be it known that I, THOMAS BINNIE DRYBROUGH, a subject of the King of Great Britain and Ireland, residing at Kensington, in the county of London, England, have invented Improvements in Coin-Freed Apparatus, of which the following is a specification.

This invention relates to coin-freed apparatus of the kind in which moving or changing pictures, figures, machines or the like are exhibited upon the insertion of a coin. While it is desirable, in order to attract custom, that the exhibits should be visible to passers-by, the revenue from such machines is liable to considerable curtailment if the exhibits when moving or changing can be seen by more than one person at a time.

According to the present invention there is combined with coin freed apparatus a curtain, screen, blind or the like device which, though normally not obscuring the contents of the case in which the exhibits are arranged, is adapted to be moved, after the insertion of a coin, to such a position as to prevent any view of the exhibit being obtained except through a peep-hole or holes so long as the exhibit is moving or changing.

The means for actuating the curtain, screen, blind or the like device may be variously arranged. Thus where clockwork or electrical mechanism freed by the inserted coin, is employed to move or change the exhibit, the said mechanism may be arranged to move the curtain, screen, blind or the like so as to obscure the view before or at the same time as the movement or changing of the exhibit commences and to restore the curtain, screen, blind or the like to its normal open position when the movement or changing of the exhibit ceases.

Referring to the accompanying drawings Figure 1 is, a vertical sectional side view of coin freed apparatus embodying the invention, Fig. 2 is a back elevation with parts of the casing broken away; Figs. 3 and 4 are detail views and Fig. 5 is perspective view of the movable screen detached from the apparatus.

The apparatus shown comprises a casing *a* divided by a floor *b* into a lower compartment *c* containing the coin freed clockwork and an upper compartment *d* in which the exhibit (not shown) is located and which has a glazed front *e*. From the center of

the roof of the upper compartment depend pivots *f* on which are mounted parts of arms *g* carrying at their free ends two partly circular shutters *h* (Figs. 1, 2 and 5) which are shown turned back so that they occupy a position behind the contents of the compartments. The shutters *h* are each connected by a link *i* to a lever *j* extending through the floor *b* into the compartment *c* and connected by link *k* to a lever *l* pivoted at the bottom of the compartment *c* and provided with a weighted arm *m* tending to move it so as to turn the shutters about their pivots into a position in which they will meet across the front of the casing and obscure the contents of the compartment *d*, except from inspection, through peep holes *h'* which are then the distance apart of a person's eyes. The lever is adapted to be moved at the required times into the position shown by a cam *n* actuated by coin freed clock-mechanism of any suitable type. By way of example an arrangement is illustrated in which one arm *o* of a bent lever *o*, which acts as a stop to the clock mechanism, extends through a slot across the coin chute *p* (Figs. 1 and 4) when the end of its other arm is in the path of a cross pin *q* on the governor fan spindle *q'* of the clock mechanism. The weight of an inserted coin moves the lever *o* clear of the pin *q* thus freeing the clock mechanism which at once commences to rotate the cam *n* and thus allow the lever *l* to move the shutters to the front of the compartment *d*. The lever *o* has pivoted to it a rod *r* that extends through a guide *s* fixed to the clock case and to the rod *r* is pivoted an elongated detent *t* working in a slot in the guide *s*, a light spring *u* tending to draw the detent toward the rod and also to draw the lever *o* into the position shown in Fig. 1. On the same spindle as the cam *n* is a snail *v* provided with a crank pin *w*, the snail being beneath the rod *r* with the pin *w* extending across the detent.

After being raised by the coin, the detent engages the guide *s* so as to clear the pin *w*, and holds the parts in the position shown in Fig. 3 until the freed clock mechanism has rotated the snail *v* and cam *n* back to the positions shown in Fig. 1, by which time the cam will have moved the lever *l* and the shutters and the pin *w* will have disengaged the detent *t* from the guide *s*, thus allowing the lever *o* to reengage the pin *q* and stop

the clock mechanism, the parts then all being in the positions shown in Fig. 1. The snail *v*, which is adapted to act upon the end of the rod *r*, is provided to insure the movement 5 of the parts to the position shown in Fig. 3 in the event of the coin not having imparted sufficient movement of the lever *o* to effect engagement of the detent with the guide and possibly being held in the chute by the end 10 of the lever *o*, it being understood that the movement of the lever *o* has been enough to release the motor control pin *q*. The fact that in such a circumstance the detent *t* may not have been raised clear of the pin *w* is 15 immaterial because it will be displaced laterally by such pin at the same time as the rod *r* is being longitudinally advanced by the snail *v* in order to ultimately engage the detent *t* with the guide *s*.

20 As will be understood the clockwork may be adapted to impart movement or change to the exhibit in any way that may be convenient and the means will vary according to the type of exhibit, the movements thereof 25 or the change thereof, as by varied illumination, that may be desired; for this reason an exhibit is not shown neither is any means for moving or changing it. The timing of the opening and closing of the shutters is 30 such that to obtain a full view of the exhibit during the period of movement or change it is necessary to view it through the peep holes in the closed shutters.

What I claim is:—

35 1. Apparatus of the kind referred to, comprising a casing for exhibits, a screen provided with a peep hole arrangement and means for moving the same from a position where normally a free display of the exhibits 40 results to a position such as to obscure the exhibits from the view of all but one individual at a time through such peep hole arrangement, coin freed mechanism adapted to operate the exhibits and said means and

45 maintain the partial obscurity for a predetermined time, and means controlled by the coin freed mechanism for operating the exhibits during the period of partial obscurity.

2. Apparatus of the kind referred to, comprising a casing for the free display of exhibits, screening means normally occupying a position permitting the exhibits to be visible to passers-by, said screening means having a peep hole arrangement, and coin freed mechanism whereby the screen can be moved 50 to temporarily obscure the exhibits from onlookers in general, at the same time bringing the peep hole arrangement into position for use of any single individual.

3. Apparatus of the kind referred to, comprising a casing for the display of exhibits, coin freed mechanism adapted to modify or change the appearance of such an exhibit, and movable screening means, provided with a peep hole arrangement, operated by such 65 coin freed mechanism for moving said screening means from a position where normally it affords a free view of the exhibits, to a position for obscuring vision of the exhibit to all but one individual during the 70 time it is being modified and thereafter restoring the screening means to normal position to remove the obscurity and restore the general visibility.

4. Apparatus of the kind referred to, comprising a casing for exhibits, a front through which the exhibits can be normally viewed by passers-by, a pair of shutters each having a permanently open peep hole and normally arranged behind the exhibits, and 80 coin freed mechanism whereby said shutters can be moved to temporarily close the front, bringing the peep holes together the distance apart of a person's eyes.

Signed at consulate of the United States 85 of America, Republic of France, city of Lyon, this 2nd day of April, 1920.

THOMAS BINNIE DRYBROUGH.
